UNITED STATES PATENT OFFICE.

CHARLES E. BLAKE, SR., OF SAN FRANCISCO, CALIFORNIA.

DESIGN FOR A DENTAL PUNCH.

SPECIFICATION forming part of Design No. 21,771, dated August 9, 1892.

Application filed June 27, 1892. Serial No. 438,209. Term of patent 14 years.

To all whom it may concern:

Be it known that I, CHARLES E. BLAKE, Sr., a citizen of the United States, residing at San Francisco, State of California, have invented and produced a new and original Design for Dental Punches; and I do hereby declare the following to be a full, clear, and exact description of the same, reference being had to the accompanying drawings, forming a part thereof.

My invention relates to a new design for dental punches; and the essential feature of such design consists in the particular shape of the handle A of the punch, as herein shown and described, said handle being oval or approximately cylindric in cross-section and

being slightly rounded or tapered near each end.

Figure 1 is a perspective view of a dental punch with its handle embodying my design. Fig. 2 is a transverse or cross section of the handle.

What I claim is—

The design for a dental punch, substantially as herein shown and described. 25

In testimony whereof I affix my signature in presence of two witnesses.

CHAS. E. BLAKE, SR.
